ROASTING APPARATUS

Kenneth W. Macdonald, Watertown, Mass., assignor to Peter J. Linstrom, Medford, Mass., and Aloysius L. Mahoney, Jamaica Plain, Mass.

Application February 13, 1932, Serial No. 592,697

5 Claims. (Cl. 219—35)

This invention relates to certain improvements in a type of baking or roasting machine which is primarily intended for use in roasting small articles, such as Frankfurts.

5 The objects of my invention are to provide a roasting machine of this type with which all portions of the articles which are to be roasted will be uniformly operated upon, and a continuously roasting operation may be performed 10 on a large number of articles which may be successively supplied and removed, or with which all the articles which the machine is adapted to receive may be supplied before the roasting operation is started and removed when the operation is finished.

Another object of my invention is to provide in connection with the means for securing the results above referred to, a conveniently arranged storage oven in which rolls may be heated and 20 the roasted Frankfurts may be kept warm.

These and other features of the invention will be best understood and appreciated from the following description of a preferred embodiment thereof, selected for purposes of illustration and 25 shown in the accompanying drawings, in which—

Fig. 1 is a view partly in front elevation, and partly in central vertical sections of a preferred embodiment of my invention.

30 Fig. 2 is a sectional plan view, at line 2—2 of Fig. 1.

Fig. 3 is a similar view, at line 3—3 of Fig. 1.

Figs. 4 and 5 are detail views of the spindle rotating and the heating means.

35 As shown in the drawings, an outer casing is provided, which comprises a pedestal portion 1, on which a cylindrical top-portion 2 is mounted in an axially vertical position. A hollow and preferably fixed post 3 is mounted vertically in 40 the middle of the pedestal 1 and extends upward into the lower part of the top-portion 2. A sleeve 4 is mounted for rotation in the post 3 and is supported thereon by a step bearing 5, and a circular table, or carrier 6 is rotatably 45 mounted on said post 3 and is supported on said sleeve, a simple clutch connection, as teeth 7, being provided therebetween, so that when the sleeve is driven the table will be rotated about a vertical axis. Means for rotating sleeve 4 is provided, which are shown as comprising a motor x arranged to drive a worm gear 8 through a series of speed reducing gears, the gear 8 being engaged with gear teeth on the periphery of the sleeve 4, so that when the motor is driven 50 55 the table 6 will be slowly rotated, the speed of

rotation being made to correspond to requirements.

A series of spindles 10 are mounted for rotation about vertical axes, in the peripheral portion of the carriers 6, said spindles being regularly spaced and circularly arranged with relation to the axis of the carrier, and having a swiveled connection therewith. A gear or sprocket 11 is mounted on the lower end of each spindle, beneath the carrier, and each gear is arranged in mesh with a circular rack or chain 12, which is fixed on a circular flange 13 formed on the pedestal 1. Each spindle 10 has a series of spring arms 14, which, in the present instance, are designed to hold an ordinary Frankfert in upright position, as indicated in Fig. 1. A series of holders are thus provided which are moved in a circular path by the carrier 6 and are slowly rotated as they are carried in said path by the engagement of the gears 11 with the 60 65 70 75 fixed rack 12.

An oven for heating rolls and storing the rolls and Frankfurts may be constructed as follows. A flat, circular metal plate 15 is mounted horizontally on the upper end of the post 3, and a cylindrical wall 16 of thin sheet metal is mounted on the peripheral edge of said plate 15 and extends upward above the level of the cylindrical outer casing 2. A series of electrical heating elements 18 are mounted on the outer side of said wall 16, so that they are held in proximity to the holder arms 14 and in heating relation to the oven. The wall 16 may be perforated opposite said elements, as shown in Fig. 5, or it may be imperforate. The electrical connections 19 extend upwardly through the post 3 to the heating elements. A perforated basket 22 is preferably provided for the oven compartment formed within the plate 15 and circular wall 16, said basket being held out of direct 80 85 90 95 contact with the bottom and sides of the compartment by any suitable means. A cover or closure 24 is provided for the compartment, which is fitted to the top edge of the wall 16, and, when removed, permits ready access to the 100 contents of the basket 22.

The wall 16 extends to a somewhat higher lever than the outer side 2 of the casing and the annular compartment provided therebetween is closed by two curved cover sections 25, 26, which are hinged to the outer casing at their middle portions, so that each may be swung upward and outward to permit ready access to the entire space between the casing and wall 16. Said cover sections are arranged to meet at 105 110

two corresponding ends and to terminate short of each other at the other two ends to provide an opening 28 through which an article in a holder may be placed in position and removed.

5 In operating the above-described device the motor rotates the circular carrier 6 at a low speed and the holders 14 are slowly rotated constantly as they are carried in a circular path in proximity to the heating elements 18, which 10 are mounted on the wall 16. By this arrangement the portions of the Frankfurts in the holders which are directly exposed to the heat from the elements 18 are constantly changed, so that the effect of the roasting operation will 15 be uniform.

Two methods of roasting may be employed. The covers 25, 26 may be closed and a Frankfurt may be inserted in each holder as it passes beneath the opening 28. The heat will be so 20 regulated, with relation to the speed of rotation of the carrier that, during the time required for a single rotation of the carrier, the roasting operation on a Frankfurt in a holder will be completed. The operation may thus be carried 25 on continuously by removing a Frankfurt from each holder, as it is moved into register with the opening 28, and by placing another in position before the holder has been moved past the opening.

30 Also, if desired, the covers 25, 26 may be lifted and all the holders filled before the machine is started and then they may be emptied at one time when the operation is finished.

The space within the wall 16 will become 35 heated by the heating elements 18 and may be used for storage purposes of articles which have been roasted, and also it may be used for heating the rolls in connection with which Frankfurts are usually sold.

40 As thus arranged ready access may be had to the storage oven while the roasting operation is going on.

I claim:

1. In a roasting apparatus, a vertical post, 45 an oven supported on the post and having a cylindrical side wall and a closure for the top thereof, a horizontally disposed and rotary carrier mounted on the post beneath the oven and extending beyond said side wall, a series of 50 holders mounted in spaced relation on the peripheral portion of said carrier to rotate about vertical axes and to be carried in a circular path in proximity to said side wall, a fixed outer casing having a portion encircling said holders and 55 providing an annular space between the same and said side wall in which said holders are carried, heating elements adjacent to said side wall within said space for heating the space and oven, and interengaging means on said casing 60 and said holders for causing rotation of the

holders as they are moved circularly by said carrier.

2. In a roasting apparatus, a fixed vertical post, an open oven on the top portion of said post comprising a horizontally disposed bottom 80 having a cylindrical side wall and a closure for the top thereof, a circular, horizontally disposed carrier rotatably mounted on said post beneath said bottom and extending beyond said side wall, a series of holders mounted in spaced relation on the peripheral portion of said carrier to rotate about vertical axes and to be carried in a circular path in proximity to said side wall, a fixed outer casing having a portion 85 encircling said holders and providing an annular space between the same and said side wall in which said holders are carried, heating elements adjacent to said side wall and laterally of said holders, and interengaging means on said casing and said holders for causing rotation 90 of the holders as they are moved circularly by said carrier.

3. The apparatus defined in claim 1, plus 95 foraminous means within said cylindrical side wall for holding food elements stored therein from engagement with said side wall, and said side wall being perforated to permit the passage of heat from said heating elements inwardly through the wall.

4. The apparatus defined in claim 1, plus 100 removable cover sections resting on said side wall and outer casing and spanning the gap therebetween in a manner providing a cover over said annular space above said holders therein.

5. In a roasting apparatus, a vertical post, a 110 fixed outer casing about the post and having a cylindrical top portion of relatively large diameter, means mounted on the top end of the post and having a vertically extending cylindrical wall of relatively large diameter inwardly 115 and spaced from the cylindrical top portion of the casing in a manner providing a circular chamber therebetween, heating elements adjacent to the outer face of the wall, a rotary element on the post having a toothed upper end, 120 a rotary carrier on the post having a toothed lower end in clutching engagement with the toothed upper end of the rotary element, the carrier extending outwardly to the circular chamber, a series of spindles circularly mounted 125 in spaced relation on the peripheral portion of the carrier, article holding means on each spindle and extending upwardly into the circular chamber, a circular rack carried by the casing concentrically of the post, gears respectively carried by the spindles and in mesh with the rack, and means for rotating the rotary element.

KENNETH W. MACDONALD.

CERTIFICATE OF CORRECTION.

Patent No. 1,971,012.

August 21, 1934.

KENNETH W. MacDONALD.

It is hereby certified that error appears in the printed specification of the above numbered patent requiring correction as follows: Page 2, line 79, claim 2, strike out the word "open"; and that the said Letters Patent should be read with this correction therein that the same may conform to the record of the case in the Patent Office.

Signed and sealed this 11th day of September, A. D. 1934.
